UNITED STATES PATENT OFFICE.

JOSEPH B. CONSOLLA, OF TUXEDO PARK, NEW YORK.

DESIGN FOR A BOOTJACK.

SPECIFICATION forming part of Design No. 34,456, dated April 30, 1901.

Application filed April 3, 1901. Serial No. 54,224. Term of patent 7 years.

To all whom it may concern:

Be it known that I, JOSEPH B. CONSOLLA, a citizen of the United States, residing at Tuxedo Park, in the county of Orange and State of New York, have invented and produced a new and original Design for Bootjacks, of which the following is a specification, reference being had to the accompanying drawing, forming part thereof, said drawing being a perspective view of my newly-designed bootjack.

As shown in the drawing, the leading or material feature of my design consists of the form of the bootjack, which comprises a base ¹⁵ *a*, an upright portion *b*, connected with one end of the base, forwardly-directed side arms *c*, connected with and forming part of said base, the U-shaped opening *d*, by which the ends of said arms are separated, and the legs ²⁰ *e*, which are connected with the arms *c* and

extend downwardly and forwardly and the ends or feet of which are level with the bottom of the base portion *a*. The upright portion *b* is also provided with an opening *b*², having upright brushes *b*³ at the opposite sides ²⁵ thereof and a transverse scraper *b*⁴ at the bottom thereof.

Having fully described my invention, what I claim as new, and desire to secure by Letters Patent, is—

The design for bootjack herein shown and described.

In testimony that I claim the foregoing as my invention I have signed my name, in presence of the subscribing witnesses, this 2d day ³⁵ of April, 1901.

JOSEPH B. CONSOLLA.
